SPRING TENSION DEVICEWilbur L. Mullen, 1907 S. Dianne Ave., Evansville, Ind.
Filed Oct. 24, 1961, Ser. No. 147,313
11 Claims. (Cl. 123-188)

The present invention relates to a spring tension device, and more particularly to a new and novel spring tension device which is adapted for use with a valve spring in an internal combustion engine.

As is known, the continued use of an internal combustion engine changes the desired operative balance between the chain of components thereof including the cam shaft, the hydraulic lifter, the rocker arm and the valve, resulting in poor engine performance. The aforesaid change in balance is occasioned by the valve spring becoming weakened, where, previously, in order to re-establish the desired performance, a complicated disassembly procedure was necessary, sometimes to the point of replacing the valve spring. The preceding represented a considerable time, as well as money, expenditure.

By virtue of the instant invention, the applicant herein has invented a new and novel spring tension device for use in conjunction with the valve spring of an internal combustion engine. In its several forms, the instant spring tension device is simply and conveniently positioned for use, in either an old or a new engine, and is readily manufactured, all being features providing a minimum expenditure for the user. More specifically, the instant invention is defined by a member which, when in use, is positioned so as to either engage the valve spring or the oil deflector of a typical valve assembly for an internal combustion engine, and where means are provided to retain, or otherwise lock, the member in such position of use.

Accordingly, the principal object of the present invention is to provide a new and novel spring tension device for a valve of an internal combustion engine.

Another object of the present invention is to provide a new and novel spring tension device for a valve of an internal combustion engine which may be readily used on either an old or a new engine.

A further object of the present invention is to provide a new and novel spring tension device for a valve of an internal combustion engine which is conventionally positioned for use with a minimum disassembly of the internal combustion engine.

A still further and more general object of the present invention is to provide a new and novel spring tension device for a valve spring of an internal combustion engine which is readily manufactured and which represents a minimum cost to the user.

Other objects and a better understanding of the instant invention should become more apparent from the following description, taken in conjunction with the accompanying drawings, wherein

FIG. 1 is a diagrammatic view, partly fragmentary, and partly in vertical cross section, showing a typical valve assembly of an internal combustion engine;

FIG. 2 is a top plan view of a spring tension device made in accordance with the instant invention;

FIG. 3 is another view of the spring tension device of FIG. 2, being in vertical section, and taken at line 3-3 of FIG. 2 and looking in the direction of the arrows;

FIG. 4 is a top plan view of another spring tension device in accordance with the instant invention;

FIG. 5 is a view in vertical section of the spring tension device of FIG. 4 positioned for use, taken at line 5-5 of FIG. 4 and looking in the direction of the arrows;

FIG. 6 is a top plan view, in closed position, of another spring tension device in accordance with the instant invention;

2

FIG. 7 is a view in vertical section of the spring tension device of FIG. 6, taken at line 7-7 of FIG. 6 and looking in the direction of the arrows;

FIG. 8 is another top plan view of the spring tension device of FIG. 6, in this instance, however, showing same in an opened position;

FIG. 9 is a top plan view of another spring tension device in accordance with the instant invention;

FIG. 10 is a view in vertical section of the spring tension device of FIG. 9, taken at line 10-10 of FIG. 9 and looking in the direction of the arrows;

FIG. 11 is another spring tension device in accordance with the instant invention;

FIG. 12 is a detailed view of one of the cooperating portions of the spring tension device of FIG. 11, taken at line 12-12 of FIG. 11 and looking in the direction of the arrows;

FIG. 13 is a view in vertical section of the spring tension device of FIG. 9 positioned for use, taken at line 13-13 of FIG. 9 and looking in the direction of the arrows;

FIG. 14 is a top plan view of one of the two cooperating portions of the spring tension device of FIG. 9; while,

FIG. 15 is a top plan view of the other of the two cooperating portions of the spring tension device of FIG. 9.

For the purposes of promoting an understanding of the principles of the invention, reference will now be made to the embodiments illustrated in the drawings and specific language will be used to describe the same. It will nevertheless be understood that no limitation of the scope of the invention is thereby intended, such alterations and further modifications in the illustrated devices, and such further applications of the principles of the invention as illustrated therein being contemplated as would normally occur to one skilled in the art to which the invention relates.

Referring now to FIG. 1, the applicant's new and novel spring tension device 10 is used in conjunction with a commonly known overhead valve assembly of an internal combustion engine, the latter as typically found in an automobile. In any event, the components defining the aforesaid assembly broadly include a valve head 14 having a stud 15 positioned thereon which receives a rocker arm assembly 16, the latter being defined by a rocker arm 16a, a rocker arm pivot ball 16b, and a nut 16c. One portion of the rocker arm 16a is engaged by a push rod 18, the latter connecting to a hydraulic lifter and cam shaft (neither of which are shown in the drawings).

Another portion of the rocker arm 16a is engaged by the stem of a valve 20, where such extends through an opening 14a in the valve head 14. A valve spring 22 encircles the valve 20 and its bottom end is seated in a recessed portion 14b in the valve head 14, with an oil deflector 24 typically being positioned on its top end.

55 A typical overhead valve assembly further includes a two-part valve keeper 23, a cap 21 which retains the valve keeper 23 in position through the tension of the valve spring 22, and rubber gasket 25 for positioning the valve keeper 23, as well as for sealing purposes. The assembly is typically closed by a cover 26 made from metal or like material.

In any event, when the force of the valve spring 22 becomes lessened because of the usage of the internal combustion engine, an unbalance results between the push rod 18, the hydraulic lifter and the cam shaft, on one end of the rocker arm assembly 16, and the valve 20 on the other end thereof. The applicant's new and novel invention foresees the restoration of balance by the use of a spring tension device, of the types to be described herebelow, which is typically inserted between the valve spring 22, or the oil deflector 24, if the latter is used, and the cap 21.

With reference to FIGS. 2 and 3, a typical spring tension device 30 in accordance with the instant invention comprises cooperable components 30a and 30b, which, when assembled, define an opening, having a downwardly flared rim. The latter permits the ready positioning and retaining of the spring tension device 30 either on the valve 22 or on the oil deflector 24 (see FIG. 1). In any event, use of the spring tension device 30 provides the desired balance for good engine performance.

FIGS. 4 and 5 disclose another form of the instant invention, in this instance an embodiment having particular adaptability for use on new internal combustion engines. In this regard, the spring tension device 40 of FIGS. 4 and 5 comprises a threaded base 40a having a flange 40b at one end thereof. A cooperating member 40c is adapted to move along the threaded base 40a, thereby permitting the regulation of the spacing between such components and, hence, the tension on the valve spring 22.

In this form of the invention, the movable cooperating member 40c of the spring tension device 40 can be "self-locking" at any desired tension position or, for example, may be locked through a twisted wire arrangement (not shown) extending from flange 40b of the threaded base 40a to the cooperating member 40c. Additionally, it may also be desirable to have the desired positioning maintained by a torsion spring (not shown) having ends which respectively extend into the aforesaid flange 40b and the cooperating member 40c. Similarly, a cotter pin (not shown) may also be used for the same purposes.

With reference to FIGS. 6, 7 and 8, another spring tension device 50 is disclosed therein comprising arcuate portions 50a and 50b, hinged together at 50c. The ends of the arcuate portions 50a and 50b each have roughened surfaces, at 50d (see FIG. 7), so that when these arcuate portions 50a and 50b are rotated to a closed position, upon positioning for use, locking thereof is effected. Instead of frictional engagement, it should be apparent that a detent may be formed in each of the ends of the arcuate portions 50a and 50b, and, further, that gripping arms may extend from such ends in a manner similar to those arms adjacent the hinge 50c.

A preferred form of spring tension device 60 is disclosed in FIGS. 9, 10, 13, 14 and 15, where such spring tension device is defined by symmetrical parts 60a and 60b, each having oppositely disposed, in consecutive order, upstanding tabs 60c formed thereon. Corresponding detent type locking arrangements 60d are provided at the ends of each of the parts 60a and 60b where, in assembly, and in the instance where an oil deflector 24 is employed, the parts 60a and 60b defining the spring tension device 60 are fitted between such oil deflector 24 and the cap 21 (see FIG. 13). It should be apparent that the upstanding tabs 60c serve to position the spring tension device 60 with reference to the oil deflector 24 and to the cap 21. Moreover, it should be apparent that the parts 60a and 60b of the spring tension device 60 may be retained in assembled relationship through the alternative use of lanced burrs or other types of projections.

With reference now to FIGS. 11 and 12, still another modified spring tension device 70 is shown therein, in this instance being defined by portions 70a and 70b, each having a step-like configuration 70c in side view, and where each are movable one with reference to the other. The modification of FIGS. 11 and 12 is particularly adaptable for new internal combustion engines but, in any event, it assumes the same position discussed hereabove, i.e. between the valve spring 22 and the cap 21, or the oil deflector 24, if the latter is employed. It should be apparent that by the choice of different steps, the portions 70a and 70b may assume different spacings with reference to each other and, thereby, provide a range of spring tension adjustments.

In any event, and from the preceding, it should be apparent that the applicant herein has provided a new and

novel spring tension device for use in conjunction with the valve spring in an internal combustion engine. The invention, in its several forms, is characterized by simplicity, in that instead of a complicated disassembled procedure previously relied upon, the instant spring tension devices are readily positioned for use, as well as positively retained for such use. It should be further apparent that the instant spring tension device provides the necessary balance for effective engine performance, and that at least two of the types of spring tensioning devices disclosed herein are susceptible for use in connection with new internal combustion engines, i.e. each have more adaptability for such use in that the valve cap, and other allied assembly, must be removed to effect the initial positioning thereof. As to subsequent use, however, each represents a variety of spacings to achieve the ultimate purposes of the invention.

Moreover, the spring tension devices described hereabove are susceptible to various changes within the spirit 20 of the invention. As indicated herein, various locking arrangements may be employed and additionally, the dimensioning as well as proportioning thereof may be varied. In this latter regard, and by way of background information, a range of thicknesses in the order of $\frac{1}{16}$ to 25 $\frac{1}{16}$ of an inch may be typically employed for the effective practice of the invention. Thus, the preceding discussion should be considered illustrative, and not as limiting the scope of the following claims.

I claim:

30. 1. In an internal combustion engine having a valve stem, a valve keeper, a valve cap and a valve spring, a spring tension device disposed around said valve stem and between said valve spring and said valve cap comprising a first and a second curved member each having end portions, and locking means disposed on said end portions retaining said first and said second curved members in assembled relationship.
2. In an internal combustion engine having a valve stem, a valve keeper, a valve cap, a valve spring, and an oil deflector disposed on said valve spring, a spring tension device disposed around said valve stem and between said oil deflector and said valve cap comprising a first and a second curved member each having end portions, and locking means disposed on said end portions retaining said first and said second curved members in assembled relationship.
3. In an internal combustion engine having a valve stem, a valve cap, a valve keeper and a valve spring, a spring tension device disposed around said valve stem and engaging said valve cap through a force exerted by said valve spring, said spring tension device comprising a first and a second curved member each having end portions, and locking means disposed on said end portions retaining said first and said second curved members in assembled relationship.
4. The structure of claim 3 where said curved members each have oppositely disposed flanges thereon defining positioning means.
5. The structure of claim 3 where said locking means on said end portions are co-operating detents.
6. In an internal combustion engine having a valve stem, a valve cap, a valve keeper and a valve spring, a spring tension device disposed around said valve stem and engaging said valve cap through a force exerted by said valve spring, said spring tension device comprising a first and a second curved member hinged together at one portion thereof, and means locking together other portions of said first and said second curved members.
7. The structure of claim 6 where said other portions of said first and said second curved members are locked together through frictional means.
8. In an internal combustion engine having a valve stem, a valve cap, a valve keeper and a valve spring, a spring tension device disposed around said valve stem and engaging said valve cap through a force exerted by

said valve spring, said spring tension device comprising a first member having a threaded body portion, and a second member movable along said threaded body portion of said first member.

9. The structure of claim 8 where means are provided to retain said first member and said second member at any desired preselected position with respect to each other.

10. In an internal combustion engine having a valve stem, a valve cap, a valve keeper and a valve spring, a spring tension device disposed around said valve stem and engaging said valve cap through a force exerted by said valve spring, said spring tension device comprising a first member and a second member, each of said first and said second members having step-like projections thereon, whereby said first member and said second member can be selectively positioned one with respect to each other.

11. In an internal combustion engine having a valve

stem, a valve cap, a valve keeper and a valve spring, a spring tension device disposed around said valve stem and engaging said valve cap through a force exerted by said valve spring, said spring tension device comprising a first member and a second member, where said second member is movable along the body of said first member.
